DESIGN FOR A PERFUME DEMONSTRATING FOUNTAIN

Fred E. Ohrenschall, Baltimore, Md.

Application November 23, 1938, Serial No. 81,321

Term of patent 7 years

To all whom it may concern:

Be it known that, Fred E. Ohrenschall, a citizen of the United States of America and a resident of the city of Baltimore, State of Maryland, has invented a new, original, and ornamental Design for a Perfume Demonstrating Fountain, of which the following is a specification, reference being had to the accompanying drawing, forming a part thereof.

Fig. 1 is a perspective view of a perfume demonstrating fountain showing my new design.

Fig. 2 is a transverse cross-sectional view taken substantially through the center of the perfume demonstrating fountain shown in Figure 1.

I claim:

The ornamental design for a perfume demonstrating fountain, as shown.

FRED E. OHRENSCHALL.
